Filed Nov. 14, 1968, Ser. No. 14,454

Term of patent 14 years

Int. Cl. D25—04

U.S. Cl. D13—1

FIGURE 1 is a view in elevation of a building in accordance with my design; and

FIGURE 2 is a view in perspective of the building of FIGURE 1, showing the circular shape of said building, with a wedge shaped section, the faces of which contain the windows and doors.

The marks on the circular sides of my building (in both figures) simulate holes in a wheel of cheese.

On the roof of my building is the figure (statue) of a mouse holding a wedge shaped object, as shown on both figures.

I claim:

The ornamental design for a building, as shown and described.
